[57] CLAIM

The ornamental design for the holder for a movie trading card, as shown and described.

DESCRIPTION

FIG. 1 is a left side isometric perspective view of the holder for a movie trading card of the present invention, the right side isometric perspective view being a mirror image thereof;

FIG. 2 is a top plan view of FIG. 1;

FIG. 3 is a left side elevation view of FIG. 1, the right side elevation view being a mirror image thereof;

FIG. 4 is a left end view of FIG. 1, the right end view being a mirror image thereof; and,

FIG. 5 is a bottom plan view of FIG. 1.

The broken lines showing the movie trading card and the inset film cell that are contained within the holder for a movie trading card of the present invention are for illustrative purposes only and form no part of the claimed design.
